GAME BOARD

Stanley J. Kolwicz, 16 Sanford Ave.,
Emerson, N.J. 07630

Filed June 28, 1972, Ser. No. 267,164

Term of patent 14 years

Int. Cl. D21—01

U.S. Cl. D34—5 SS

FIG. 1

FIG. 2

FIG. 3

FIG. 5

FIG. 1 is a perspective view of a game board showing my new design;

FIG. 2 is an end elevational view thereof, of the right hand end of FIG. 1;

FIG. 3 is a top plan view thereof;

FIG. 4 is a side elevation view thereof showing a modified base support; and

FIG. 5 is a top plan view of FIG. 4.

I claim:

The ornamental design for a game board, substantially as shown and described.
